UNITED STATES PATENT OFFICE.

ELMER A. WATTS, OF SPRINGFIELD, OHIO, ASSIGNOR TO THE MILLER IMPROVED GAS ENGINE COMPANY, OF SPRINGFIELD, OHIO, A CORPORATION OF OHIO.

SPARK-PLUG CONSTRUCTION FOR INTERNAL-COMBUSTION ENGINES.

Application filed October 23, 1924. Serial No. 745,336.

To all whom it may concern:

Be it known that I, ELMER A. WATTS, a citizen of the United States, residing at Springfield, in the county of Clark and State of Ohio, have invented certain new and useful Improvements in Spark-Plug Construction for Internal-Combustion Engines, of which the following is a specification, reference being had therein to the accompanying drawing.

My invention relates to internal combustion engines and in particular to the ignition apparatus therefor.

It is my object to provide a readily controlled ignition apparatus for use in internal combustion engines particularly those of large size and horse power used in localities where gas is present and where safety is desired in connection with the ignition apparatus.

It is my object to provide a sealed spark plug construction which will minimize the danger of this apparatus when in the presence of gases.

It is a further object of my invention of providing a dual ignition system having this protection feature so that one spark plug can be rendered inoperative while the other is functioning.

It is the object of my invention of having the means to alternately use the plugs for any cylinder, sealing the plug which is not used so that the plug which is inoperative can be removed and replaced without releasing the load on the engine.

Referring to the drawings:

Figure 1 is a section through one end of an internal combustion engine and in particular through the inlet valve casing and inlet valve, showing in section the spark plug casing with the ignition apparatus such as plugs and contact wires in position, together with the control mechanism for controlling the application of the current to the particular spark plug in action;

Figure 2 is a plan view of this mechanism with the cover removed; and

Figure 3 is a bottom plan view showing the sealing mechanism for the spark plug which is inoperative.

Referring to the drawings in detail, 1 indicates the outside casing of a cylinder head construction which contains the water passageways 2 for carrying the cylinder head of the valve casings of which 3 is the inlet

valve casing controlled by the inlet valve 4. 5 is the inlet passageway which communicates around the valve 4 with the passageway 6 which leads into the engine. The valve casing 3 is a cylindrical member having the upper end thereof open, but adapted to be sealed by the bottom plate 7 resting on the shoulders 8 of the inlet valve casing 3. This bottom plate has interposed between it and the casing 3 the packing ring 9. The incoming fuel passes beneath this bottom plate and sweeps over the spark plugs 10 which are mounted in such plate and have their lower ends projecting into the path of the incoming gases which are used as fuel for the internal combustion engine of which this apparatus is a part. These plugs 10 are arranged in pairs preferably. The apertures through which the plugs project are alternately sealed by the sealing plate 11. This plate is carried on a vertical shaft 12 which projects upwardly through the plate 7 into the spark plug chamber 13 and through the spark plug chamber cap 14. On its upper end is mounted a handle 15 for controlling each of the spark plugs for rendering either inoperative. This spark plug chamber is formed by the upwardly extending cup shaped walls 16 and the bottom of the cup is formed by the bottom plate 7. These walls are provided with overhanging shoulders 17 resting on the shoulders 18 of the casing 1. Cooling fluid passes around this cup in the passageways 19. A sealing ring 20 is provided between the shoulders 17 and 18. A gas tight seal is formed at this point and also at the point of junction between the bottom plate 7 and the inlet valve casing 3.

Mounted upon the shaft 12 which has a recessed shoulder portion 21 is a collar of insulating material 22 on which is mounted a pair of blocks of insulating material 23 which carry between them a V-shaped wire 24 adapted at its outer ends to engage with terminals 25 of the respective spark plugs adjacent thereto which may be in the path of movement of such a wire. The base of this V-shaped wire is attached to a terminal 26 which in turn is connected to the main cable 27. This cable is led out through an insulating collar preferably of porcelain marked 28 which has a tapered exterior 29 fitting into a correspondingly shaped upwardly projecting collar or throat 30 formed

integrally with the cap 14 so that no leakage of gas can take place at this point.

Thus the entire contact apparatus for making or breaking the circuit is enclosed in a sealed chamber to prevent accident due to the presence of gases in this chamber which might be ignited by any arcing or stray currents.

It will be understood that I desire to comprehend within my invention such modifications as may be necessary to adapt it to varying conditions of use.

Having thus fully described my invention, what I claim as new and desire to secure by Letters Patent, is:—

1. In an internal combustion engine, a valve casing, an ignition apparatus consisting of a spark plug, a source of current supplied thereto by a conduit, said plug and conduit at one end being hermetically sealed in a chamber, the terminals of the spark plug projecting through one wall of said chamber for access to incoming fuel, said chamber having the bottom thereof forming a detachable top for a valve casing.

2. In an internal combustion engine, a main casing, a valve casing, an ignition apparatus consisting of a spark plug, a source of current supplied thereto by a conduit, said plug and conduit at one end being sealed in a chamber, the terminals of the spark plug projecting through one wall of said chamber for access to incoming fuel, said chamber having the bottom thereof forming a detachable top for the valve casing, and having portions on the side walls thereof to rest on the outside of the main casing containing cooling fluid for passage around the valve casing and the spark plug chamber.

3. In an internal combustion engine, an ignition apparatus consisting of a spark plug, a source of current supplied thereto by a conduit, said plug and conduit at one end being hermetically sealed in a chamber, the terminals of the spark plug projecting through one wall of said chamber for access to incoming fuel, and means in said chamber adapted to make the contact between the conduit and the spark plug or break it.

4. In an internal combustion engine, an ignition apparatus consisting of a spark plug, a source of current supplied thereto by a conduit, said plug and conduit at one end being hermetically sealed in a chamber, the terminals of the spark plug projecting through one wall of said chamber for access to incoming fuel, means in said chamber adapted to make the contact between the conduit and the spark plug or break it, and means outside of said chamber for controlling said making and breaking of the circuit.

5. In an internal combustion engine, an

ignition apparatus consisting of a spark plug, a source of current supplied thereto by a conduit, said plug and conduit at one end being hermetically sealed in a chamber, the terminals of the spark plug projecting through one wall of said chamber for access to incoming fuel, means in said chamber adapted to make the contact between the conduit and the spark plug or break it, means outside of said chamber for controlling said making and breaking of the circuit, and means outside of said chamber for sealing the terminals of said plug when the current is cut off by breaking the circuit.

6. In an internal combustion engine, an ignition apparatus consisting of a spark plug, a source of current supplied thereto by a conduit, said plug and conduit at one end being hermetically sealed in a chamber, the terminals of the spark plug projecting through one wall of said chamber for access to incoming fuel, and means controlled from the outside of the chamber for sealing said spark plug when the circuit is broken.

7. In an internal combustion engine, an ignition apparatus consisting of a hermetically sealed chamber, an electrical conduit conveyed through a sealed opening into said chamber, a pair of spark plugs mounted in said chamber having their terminals projecting through the wall thereof and exposed on the outside of the chamber, a contact member connected to said conduit and adapted to be moved by means exterior of said chamber, said contact member being adapted to render both plugs inoperative or engage either one of said plugs for rendering it operative.

8. In an internal combustion engine, an ignition apparatus consisting of a hermetically sealed chamber, an electrical conduit conveyed through a sealed opening into said chamber, a pair of spark plugs mounted in said chamber having their terminals projecting through the wall thereof and exposed on the outside of the chamber, a contact member connected to said conduit and adapted to be moved by means exterior of said chamber, said contact member being adapted to render both plugs inoperative or engage either one of said plugs for rendering it operative on the outside of said chamber and controlled by said ignition controlling means for sealing that plug which is rendered inoperative.

9. In an internal combustion engine, a cylinder head casing, an inlet valve casing therein having in one portion an inlet passageway and in another portion an outlet passageway, and a top formed in said valve casing along the path of the incoming fuel by a bottom plate mounted on said valve casing, a cup mounted on said bottom plate, spark plugs projecting through said cup into said valve chamber, a sealed top for said cup, a

conduit for electric current projected into said cup but sealed where it passes through the sealed top for said cup, and means on the outside of the said cup for controlling the 5 operation of said spark plugs in the cup.

10. In an internal combustion engine, a cylinder head casing, an inlet valve casing therein having in one portion an inlet passageway and in another portion an outlet passageway, and a top formed in said valve casing along the path of the incoming fuel by a bottom plate mounted on said valve casing, a cup mounted on said bottom plate, spark plugs projecting through said cup into said 15 valve chamber, a sealed top for said cup, a conduit for electric current projected into said cup but sealed where it passes through the sealed top for said cup, and means on the outside of the said cup 20 for controlling the operation of said spark plugs in the cup, and means controlled by the same means for sealing the plug which

is not in operation where it projects into the inlet casing through the bottom plate.

11. In an internal combustion engine, a 25 cylinder head casing, an inlet valve casing therein having in one portion an inlet passageway and in another portion an outlet passageway, a top formed in said casing along the path of the incoming fuel, a bottom plate mounted on said valve casing, a cup mounted on said bottom plate, spark plugs projecting through said cup into said valve chamber, a sealed top for said cup, a 30 conduit for electric current projected into said cup but sealed where it passes through the cap for said cup, and means on the outside of the said cup for controlling the operation of said spark plugs in the cup, 35 said conduit being connected to either of the 40 plugs by a V-shaped contact wire carried on insulation blocks mounted on a shaft.

In testimony whereof I affix my signature.

ELMER A. WATTS.
